[57] CLAIM

The ornamental design for a display stand for bakery products or the like, substantially as shown.

DESCRIPTION

FIG. 1 is a left front perspective view of a display stand for bakery products or the like, showing my new design;

FIG. 2 is a side elevational view taken from the right of FIG. 1;

FIG. 3 is fragmentary left perspective view of the top portion thereof; and

FIG. 4 is a fragmentary cross-sectional perspective view taken along line 4—4 of FIG. 1.
